US00D888713S

(12) **United States Design Patent** (10) Patent No.: **US D888,713 S**
(45) Date of Patent: **** Jun. 30, 2020**

(54) **WIRELESS COMMUNICATION DEVICE**

(71) Applicant: **Yokogawa Electric Corporation**,
Musashino-shi, Tokyo (JP)

(72) Inventors: **Hiroki Tabata**, Musashino (JP); **Naoto Takano**, Musashino (JP); **Mitsuhiro Kamiya**, Musashino (JP); **Keiichi Sasaki**, Musashino (JP)

(73) Assignee: **Yokogawa Electric Corporation**,
Tokyo (JP)

(**) Term: **15 Years**

(21) Appl. No.: **29/683,949**

(22) Filed: **Mar. 18, 2019**

(57) **CLAIM**

The ornamental design for a wireless communication device, as shown and described.

DESCRIPTION

FIG. 1 is a perspective view of front, top and right side view of a wireless communication device showing our new design;

FIG. 2 is a perspective view of rear, bottom and left side view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the wireless communication device that form no part of the claimed design.
